UNITED STATES PATENT OFFICE.

FRANK DAVID PELLETIER, OF KANSAS CITY, MISSOURI.

CLOTHES-RACK.

1,047,694.

Specification of Letters Patent. Patented Dec. 17, 1912.

Application filed March 20, 1912. Serial No. 685,118.

To all whom it may concern:

Be it known that I, FRANK DAVID PELLETIER, a citizen of the United States, and a resident of Kansas City, in the State of Missouri, have invented certain new and useful Improvements in Clothes-Racks, of which the following is a specification.

My invention relates to clothes racks, and particularly to devices of this character which are capable of being folded or collapsed when not in use, both for the purpose of occupying as little space as possible and to present a more sightly appearance.

The invention further has for its object to produce a device of this character which may be "knocked down" or collapsed to facilitate storage or transportation.

Devices of this character as heretofore constructed consisted usually of a fixed standard or casing having slidably mounted therein a supporting member carrying collapsible clothes hooks or pegs, whereby the supporting member might be telescoped entirely within the fixed standard when the rack is not in use, and might be drawn out to operative position, such action at the same time throwing the clothes hooks or pegs into operative position. My invention, on the other hand, while retaining many of the desirable features of such a construction is designed primarily as a self-contained clothes rack with proper support therein, and as a means for folding up and concealing the clothes hooks or pegs when not in use, so that the device will present a sightly appearance and at the same time may be readily transported from place to place.

With these objects in view, the invention consists in the construction and arrangement of parts, embodiments of which are illustrated in the accompanying drawings, in which—

Figure 1 is a side elevation and partial section of a clothes rack embodying my improvements. Fig. 2 is a partial elevation in section of the standard of the rack shown in Fig. 1, collapsed for transportation or packing. Fig. 3 is a horizontal sectional view on the line 3—3 of Fig. 1. Fig. 4 is a view in elevation of a rack similar to that shown in Fig. 1, mounted upon a suitable wall bracket, showing the sleeve member in its lowered position. Fig. 5 is a vertical sectional view, partially in elevation, of the device shown in Fig. 4, showing said sleeve member in its elevated position. Fig. 6 is a

horizontal view on the line 6—6 of Fig. 4. Fig. 7 is a detail view in section of the hook inclosing sleeve employed with the device. Fig. 8 is a partial sectional view of a form of clothes hook embodying one aspect of my invention. Fig. 9 is a view similar to Fig. 8, showing a modified mounting for the clothes hook. Fig. 10 is a detail view of parts shown in Fig. 9.

In the embodiment of my invention illustrated in Figs. 1 to 3 inclusive, the device consists of a standard comprising folding sections 1 and 2, connected by a suitable link member 3, as shown in Fig. 2. The lower end of the lower section is provided with a dowel pin or post 4, removably mounted in a suitable aperture 5 in a supporting base 6. The sections of the standard may be drawn out from metal, preferably brass, either in the form shown in Fig. 3, or the standard may be formed of a pair of angle members suitably secured together in substantially the relative position indicated in Fig. 3. In any event, the standard as shown preferably comprises a plurality of wings or flanges 7—7, which in themselves form suitable channels for the reception and stowing of the clothes hooks 8—8. Within the broadest aspect of my invention, these clothes hooks may be of any desired form, but in the device here shown, I prefer to employ one or the other of the structures illustrated in Figs. 8 and 9. In Fig. 8, the hook 8 is provided at its inner end with an enlargement or curved portion 9 of circular form, which fits within a circular casing 10 secured in a properly shaped aperture 11 in one of the standard flanges 7. In this construction it will be seen that when the clothes hook is extended, the neck 12 thereof bears upon the lip 13 of the casing 10, whereby the hook is supported in operative position. It will likewise be seen that the hook may be readily folded upward and collapsed into the channel between adjacent flanges.

To collapse the clothes hooks and conceal the same when not in use, I provide the sliding sleeve 14, Figs. 1, 2 and 3, freely movable along the sections of the standard and having preferably an arc-shaped block 15 secured thereto by a screw 16, which block fits within one of the channels between adjacent standard flanges and prevents rotary movement of the sleeve upon the standard. In addition to forming a closure for the clothes hooks, this sleeve

forms a convenient lock to hold the two sections of the standard rigidly in alinement when the rack is in use. To this end, the block 15 carries a spring locking arm or tongue 17 having a stud 18 on its extremity adapted to take within an aperture 19 in the lower section, whereby when the sleeve is in the position indicated in Fig. 1, spanning the junction between the two sections, said sections are held rigidly in alinement. When, on the other hand, the sleeve 14 is in position to close the clothes hooks, said stud 18 takes within a suitable aperture 20 in the upper section, and is thereby held in closing position. The locking tongue 17 is of such length that it extends somewhat below the lower end of the sleeve, whereby the stud 18 may be readily disengaged from either of the apertures 19 or 20 in order to manipulate the sleeve. It is to be understood, also, that if desired an auxiliary locking device may be employed to hold the two sections of the standard in alinement when the sleeve is in the closing position at the upper end of the standard. The upper section of the standard may be provided with a removable cap, if desired which shall serve as a finish for the upper end of the standard within or against which the upper end of the sleeve is received.

Referring now to the forms of the invention illustrated in Figs. 4, 5 and 6, the standard 22, preferably triangular in cross section, is provided with a base flange 23 and a stud 24, which may be received within a suitable aperture in a bracket arm 25 hinged at 26 to the wall or other support, as for example, the head post or head board of a bedstead, or the like. In this case the closing sleeve 27 is preferably provided with a notched lug 28, Fig. 6, fitting one of the angles of the standard to prevent rotation of the sleeve thereon, and one face of the standard is provided with a spring locking tongue 29 having a stud 30 adapted to take within an aperture 30' in the sleeve, to hold the sleeve in closing position, as indicated in Fig. 5. The mounting of the clothes hooks 31—31 in this form of the invention is illustrated in Fig. 9, in which the hook is provided with an enlargement or curved portion 32, mounted within a casing 33 similar to the casing 10 above described, said casing having an extension 34, by which it may be secured to the face of the standard by a screw 36. To further steady the casing within the hollow standard, said casing is provided with lateral wings 37—37, which rest against the flat face of the standard. The enlargement 32 of the hook 31 is provided with a stop shoulder 38 adapted to engage the lip 39 of the opening in the standard which receives the hook. Also the casing is provided with a projection 40 forming a shoulder for the

support of the hook when in operative position. The two points of support provided by the stop shoulder 38 and the projection 40 present a very strong construction for the support of unusually heavy weight upon the hooks. 70

While I have herein described particular embodiments of my invention, it is to be understood that the same may be altered in details and relative arrangement of parts 75 within the scope of the appended claims.

Having thus described my invention, what I claim as new and desire to secure by Letters Patent is:

1. A clothes rack comprising a fixed 80 standard, one or more collapsible hooks carried thereby, a hook inclosing member slidably mounted on said standard and adapted to collapse and inclose the hooks in one position and to expose the same in another position. 85

2. A clothes rack comprising a fixed standard, a base therefor, one or more hooks carried by said standard, a hook inclosing sleeve slidably mounted on said standard 90 and adapted to inclose said hooks in one position and to expose said hooks in another position, said sleeve having locking means to hold the same in either position. 95

3. A clothes rack comprising a fixed 95 sectional standard, a supporting base therefor, one or more hooks carried by said standard, and a sliding member designed to lock the said sections in operative position and in another position to unlock said sections and 100 to permit collapsing thereof.

4. A clothes rack comprising a sectional standard, a supporting base therefor, one or more collapsible hooks carried by said standard, a sleeve slidably mounted on said standard and adapted to inclose said hooks when in one position and adapted to hold said sections in operative relation when in another position, and means for locking said sleeve to said standard in either position. 110

5. A clothes rack comprising a standard having foldable sections, one or more collapsible clothes hooks carried by one of said sections, a hook collapsing member slidably carried by said standard and adapted in one 115 position to hold the sections of said standard in operative relation and in another position to collapse and inclose said hooks.

6. A clothes rack comprising a standard 120 formed of a plurality of longitudinal wings or flanges, one or more collapsible hooks carried by each flange, a hook inclosing sleeve slidably mounted on said standard and adapted to collapse and inclose said hooks in one position and expose said hooks in another position, and means for locking said sleeve to said support in either position. 125

7. In a clothes rack, a standard provided with a casing adapted to receive a hook and to permit same to be turned into either col- 130

lapsed or operative position said casing being provided with means adapted to support said hook firmly in operative position; of a hook provided with an enlargement adapted 5 to fit within said casing, said enlargement being formed of the end of said hook bent or turned into a circular form.

8. In a clothes rack, a standard provided with a casing adapted to receive a hook and 10 to permit same to be turned into either collapsed or operative position said casing being provided with a stop shoulder adapted

to support said hook firmly in operative position; of a hook provided with an enlargement adapted to fit within said casing, said 15 enlargement being formed of the end of said hook bent or turned into a circular form.

In witness whereof I have hereunto signed my name this 7th day of March 1912, in the presence of two subscribing witnesses.

FRANK DAVID PELLETIER.
